UNITED STATES PATENT OFFICE.

GEORG NENZEL, OF HERISCHDORF, NEAR WARMBRUNN, GERMANY.

APPARATUS FOR FEEDING MECHANICAL GRINDING MACHINES FOR PRODUCING WOOD PULP.

Application filed April 6, 1925, Serial No. 21,088, and in Germany February 4, 1925.

This invention relates to an apparatus for feeding mechanical grinding machines for producing wood pulp.

One object of the invention is to enable in the operation of a mechanical grinding machine a given ratio between the driving power and the specific pressure exerted on the grinding elements to be maintained and adjusted, in order firstly to be able to utilize practically all the power available at the grinding shaft under variable conditions of working, and secondly to obtain a wood pulp of uniform good quality.

A further object of the invention is to provide apparatus as above-mentioned in which rotary bodies with spirally formed surfaces are employed as feeding members for pressing forward the wood pile.

In order to be able to maintain a given ratio between the driving power of the grind stone and the pressure exerted on the wood pile which is pushed forward by the feeding members, the driving of one or more feeding members takes place by means of a variable transmission gear preferably a hydraulic coupling having a variable slip, so that the transmission ratio may be changed in accordance therewith. The variation of the transmission ratio is effected by means of a regulating device the action of which on said hydraulic transmission gear is controlled by the actual speed of the grinder shaft or the loading of the driving engine, so that with an increased number of revolutions the speed of the feeding members is increased. The pressure of the wood against the grind stone is consequently also increased and the increased rotary power of the grind stone is rendered available for producing a considerably greater quantity of wood pulp. This regulating arrangement may also be employed in continuous grinders in which the feeding of the wood pile is effected by means of feeding members having a construction which differs from the spiral rotary bodies above mentioned.

As a regulating member to obtain as infinite a variation as possible of the ratio of the transmission gear or the slip of the coupling, a centrifugal governor may be employed directly driven from the shaft of the grinder. Regulating devices may also be

used which are otherwise influenced, according to the load of the driving engine or the rotation of the grind stone shaft. This may be effected for example by means of hydraulic or gas pressure driving the grinder and dependent on the load on the engine or by means of an electric current which effects a constant alteration of the transmission gear.

The hydraulic transmission device itself is preferably formed as a liquid coupling. Instead thereof the power may also be transmitted by means of gas or steam acting within the coupling. As a liquid coupling any coupling may be used which in its construction is similar to the ordinary known hydraulic brakes as will be more particularly set forth in the detailed explanation illustrated by a drawing hereinafter set forth.

If a mechanical transmission be selected, a differential gear is preferably used, wherein one of the three members is coupled with the axles of the feeding members and the second with the drive of the grinding machine, whilst the third member of said gear is engaged by a liquid brake, the slip of which is controlled by a governor.

In addition to this automatic equalization between rotary power and pressure which facilitates the utilization of fluctuations of power arising in the operation of the grinding drive as a further feature of this invention in the apparatus serving for feeding the grinder, suitable means are provided to enable the total pressure exerted on the grind stone to be adjusted within the widest limits and thus to be adapted to the wide fluctuations such as are produced more particularly in the case of grinders operated by water power by the varying weather conditions.

Also in the case of substantially diminished driving power it is necessary for the production of a uniformly good wood pulp to allow the grind stone to run at a given minimum speed. In order to allow of this, as a further feature of the invention, the limits of the shaft formed by the feeding members and the walls are adjustable so that the size of the grinding surface can be adjusted to correspond with the amount of driving power at any time available. The specific pressure necessary for producing a

good wood pulp may exist over the diminished grinding surface without the grind stone being in consequence reduced to an inadmissible low speed.

5 The mounting of the conveying members according to this invention is carried out so that they are resiliently supported and so that the feeding members at pressures unsuitable for utilization against the wood pile 10 can yield somewhat. The object of this is to prevent the lateral pressures exerted on the feeding members which for instance may be caused by contact with a hard piece of wood, being directly transmitted to the walls 15 of the conveyor shaft.

An example of construction of the improved arrangement for mechanical power grinders is illustrated in the accompanying diagrammatic drawing showing an elevation 20 partly in section.

The wood is conveyed in a shaft 1 against a grind stone 2, by means of rotary bodies 3 having spirally formed surfaces. These rotary bodies are driven by means of worm 25 wheels 4 and worms 5. The upper bearings 6 of the rotary bodies 3 are arranged for pivotal movement about the axis of the respective worms 5. The lower bearings 7 are resiliently supported by means of springs 8. The driving worms 5 and the spring supports 8 are mounted in the frame 9, the space between said worms being adjustable by means of the threaded spindle 10 which is guided by the nuts 21 fastened on the bearings 22 of the worm 5. The spindle 10 is provided with a left-hand and a right-hand thread on opposite ends thereof.

The worm 5 is driven by means of a worm gear from the rotor 15 of a hydraulic slip 40 coupling. This slip coupling resembles in construction the well-known hydraulic brake, which is used for imposing a load upon engines or other prime movers especially for the purpose of measuring the power thereof. This brake or slip coupling consists of the cylindrical rotor 15, which is rotatably mounted within the rotatable hollow cylinder 11. The circumferential surfaces of the two cylinders 11 and 15, which 45 are facing each other, are equipped with projections, such as pins or ribs 13 and 14. The outer rotor or cylinder 11 is provided with an interior rim and a pipe 18 for conveying a liquid, preferably oil, to said outer 50 rotor 11 projects into the latter. If now liquid is passed into the outer rotor 11, while the latter is rapidly rotated, the said liquid will be distributed in the form of a ring-shaped layer over the interior circumference 55 of the rotor 11. The liquid will be carried with the pins 13 which are provided on the rotor 15, so that said liquid will act upon the pins 14, thus carrying the interior rotor 15 with it. The interior rotor 15 will thus 60 follow the rotation of the outer rotor 11 at

a somewhat smaller speed, so that a certain slip will exist between the individual speeds of the rotors. This slip will be increased, if the quantity of the oil rotating within the rotors and therewith the thickness of 70 the ring-shaped layer of oil is decreased.

The outer cylinder or rotor 11 is rotated by means of any suitable driving means from the axle 12 of the grinding machine, said driving means being for the sake of convenience not shown in the drawing. The rotor 11 is preferably turned or ground off on its outer periphery in such a manner that it may be used as a pulley. The centrifugal governor 16 is likewise driven from the axle 75 12 and exerts a controlling action upon a liquid discharge pipe 17 in such a manner that the orifice of the pipe 17 will be adjusted by the governor 16 in vertical direction. The orifice of the pipe 17 is positioned oppositely to the direction of rotation of the liquid ring within the rotors, so that a small quantity of the liquid will be absorbed by the orifice, as soon as it plunges into the surface of said liquid. In this 80 manner the slip of the hydraulic slip coupling will be regulated in dependence from the speed of rotation of the grinding stone.

I declare that what I claim is:

1. In a wood grinding machine the combination of a grinding stone, with feeding members for feeding a charge of wood blocks to said grinding stone, said feeding members forming side walls for the charge containing feeding space or shaft of the 100 grinding machine, and means for adjusting the distance between the lower ends of said feeding members for the purpose of varying the effective contact surface between the charge and said grinding stone.

2. A wood grinding machine, as specified by claim 1, having at least one of the feeding members provided with an upper bearing arranged for pivotal movement of said feeding member and with a lower bearing which is resiliently supported and tending to press said feeding member against the charge of the machine.

3. A wood grinding machine, as specified by claim 1, having at least one of the feeding members provided with an upper bearing arranged for pivotal movement of said feeding member and with a lower bearing which is provided with an adjustable spring tending to press said feeding member 115 against the charge of the machine.

4. In a wood grinding machine, the combination of a grinding stone, with feeding members for feeding a charge of wood blocks to said grinding stone, and a transmission gear interposed between said grinding stone and said feeding members, said transmission gear comprising a hydraulic slip coupling and regulating means associated therewith for varying the slip of said 120 125 130

coupling in dependence from the operating condition of said grinding stone.

5. A wood grinding machine, as specified by claim 1, having a transmission gear interposed between the grinding stone and the feeding members, said transmission gear comprising a hydraulic slip coupling and regulating means associated therewith for varying the slip of said coupling in dependence from the operating condition of said grinding stone.

10. 6. In a wood grinding machine, the combination of a grinding stone, with feeding members for feeding a charge of wood blocks to said grinding stone, and a transmission gear interposed between said grinding stone and said feeding members, said transmission gear comprising a hydraulic slip coupling having two members mounted to rotate relatively to each other, a liquid interposed between closely adjacent surfaces of said members of the slip coupling, and regulating means for varying the quantity of said liquid and therewith the relative speed of 25 the two members of said coupling in dependence from variations of the operating condition of said grinding stone.

7. A wood grinding machine, as specified by claim 1, having a transmission gear interposed between the grinding stone and the feeding members, said transmission gear comprising a liquid coupling and regulating means for controlling the quantity of liquid

in said coupling and therewith the slip of the latter in dependence from variations of 35 the operating condition of said grinding stone.

8. A wood grinding machine, as specified by claim 4, in which the slip coupling consists of an outer rotor, an inner rotor mounted within the former and a liquid interposed between said rotors, the regulating means for said slip coupling being adapted to change the quantity of said liquid 40 and therewith the slip of said coupling.

9. A wood grinding machine, the combination of a driven spindle, a conveyer or feeding shaft, grinding elements mounted on said spindle and projecting into one end of said conveyer or feeding shaft, pivotally mounted bearings at the outer end of said shaft, a threaded rotatable spindle having oppositely disposed threads at its opposite ends, frames mounted on said threaded spindle, a bearing in each of said frames supported resiliently in a lateral direction, and feeding members for conveying material to 50 said grinding elements mounted at one end in said pivotal bearings and at the other end in said resilient bearings and forming 55 limiting walls of said conveyer or feeding shaft.

In testimony whereof, I have signed my name to this specification at Breslau, Germany, this 18 day of March, 1925.

GEORG NENZEL.
